(57) **CLAIM**

We claim the ornamental design of a handle for compressed air plunger, as shown and described.

DESCRIPTION

FIG. 1 is a left side, perspective view of a plunger handle; FIG. 2 is a top plan view of a plunger handle; FIG. 3 is a right side elevational view of a plunger handle; FIG. 4 is a left side elevational view of a plunger handle; FIG. 5 is a bottom plan view of a plunger handle; FIG. 6 is a left side elevational view of a plunger handle; and, FIG. 7 is a right side elevational view of a plunger handle. The portion of the plunger handle depicted in the figure's broken lines forms no part of the claimed design. The surface shading represents the surface of the plunger handle.
